UNITED STATES PATENT OFFICE.

JOHN M. HENDERSON, OF ABERDEEN, SCOTLAND.

APPLIANCE FOR LIFTING, MOVING, AND DEPOSITING MATERIALS.

No. 823,861.

Specification of Letters Patent.

Patented June 19, 1906.

Application filed June 20, 1905. Serial No. 266,142.

To all whom it may concern:

Be it known that I, JOHN MACDONALD HENDERSON, mechanical engineer, associate member of the Institution of Civil Engineers, 5 a subject of the King of Great Britain and Ireland, and a resident of Aberdeen, Scotland, have invented a certain new and useful Appliance for Lifting, Moving, and Depositing Materials (for which an application for a 10 patent has been filed in Great Britain, No. 25,538, bearing the date November 24, 1904,) of which the following is a specification.

This invention has reference to and comprises appliances for lifting, moving, and depositing materials and which will be very useful in ship-building yards in the construction of war and other vessels and for a variety of other purposes, such as bridge-works, harbor works, open-pit excavation, and mining.

20 In carrying into practice the improvements of this invention as for use in a ship-building yard transverse girders of any suitable length and built of steel, iron, or other suitable material are carried at each end of

25 an aerial cableway on supports consisting of strong beams, preferably one at each end of the girders and hinged at their lower ends to strong foundations. The supporting-beams are preferably arranged in pairs at opposite 30 ends of the device and are inclined outwardly or away from each other, Fig. 1, as will be suitable for ship-building yards and like situations where room for anchored stays is limited or not available, the weight of the girders

35 and supporting-beams will serve wholly or in part to put the necessary tension on the cables. Between the girders one or a combination of any suitable number of cables are stretched, either fixed at both ends, fixed at 40 one end and capable of movement along the girder at the other end, or capable of such movement at both ends. When capable of movement along the girders, the ends of the cables are secured to suitable carriages capable 45 of traveling along the girders by means of horizontal and vertical wheels engaging with rails. When capable of movement along the girders, the cables may be made to move simultaneously, separately, in opposite directions simultaneously, in opposite directions singly, or a combination of any or all of these. When so arranged to move, the movements are made either with or without loads suspended. The motive power for the side 50 movement of cables is hand, steam, electric, hydraulic, pneumatic, petrol, or spirit, one

of these or a combination of two or more and the controlling apparatus for the side movement of each cable along the girder are placed at any convenient point, preferably on the 60 load-carriage. One, or it may be more, hoisting and traveling load-carriage is suspended on each cable, and each carriage is independently controlled and operated. The controlling mechanism may be located at any 65 convenient point, preferably, as shown in Figs. 5 and 6, on an inclosed platform on the hoisting and traveling load-carriage, which is always directly over the work and in the best position for the operator to see what is 70 necessary to be done. The motive power for hoisting and traveling motions for load-carriage may be hand, steam, electric, hydraulic, pneumatic, petrol, spirit, any one of these, or a combination of two or more, and in order 75 that others skilled in the art to which my invention relates may properly understand same and how it is to be carried into effect or practice I have hereunto appended four sheets of drawings, in which— 80

Figs. 1 and 2 are respectively an elevation and plan of one arrangement of my new or improved appliances. Fig. 3 is a side view of one form of the end carriages, also showing the upper end of one of the supporting-beams; and Fig. 4 is an end view of said carriage, while Figs. 5, 6 are respectively a side view and a plan of one form of load-carriage.

Referring to the drawings, as illustrated by Figs. 1 and 2, the transverse girders *a*, 90 made of any suitable length and built of steel, iron, or other suitable material, are carried at each end of the aerial cableway or cableways *b* on supporting-beams *c*, hinged at their lower ends to strong foundations *d*. 95 The beams are placed, as shown, at an angle or inclination outward and are connected by the stay-cables *e*, secured to each beam by turnbuckles or other straining or tension-regulating devices. They are also secured to strong foundations *f* beneath by the cable or like *g*. Between the end girders the cableways *b* are stretched, secured at each end to traveling carriages *h*, arranged to give transverse movement and merely indicated in 100 these views, but shown in detail to an enlarged scale in Figs. 3 and 4. A load-carriage *i*, merely indicated in these figures, but shown in detail to an enlarged scale in Figs. 5 and 6, for raising, lowering, and distributing material is sustained by each cableway *b*. Hauling-lines *j*, secured at each end to the 110

end carriage, are used to haul the load-carriages *i* to and fro and give longitudinal motion to these.

As illustrated by Figs. 3 and 4, which are respectively a side view of one form of end carriage and an end view of same, Fig. 3 also showing the upper part of a beam *c* and the end of the girder *a*, the end carriage is constructed as a strong framing carrying an electromotor *k*, which transmits motion, by means of the worm *l*, worm-wheel *m*, shaft *n*, pinion *o*, and spur-wheel *p*, to the bevel-gearing *q r s t*, to the vertical shafts *u*, on which the traveling wheels *v* are keyed or otherwise secured and which by their friction on the plates *w* of the end girder *a* cause the carriage to travel to and fro. The carriage rests by the flanged wheels *x* on the rails *y*, secured on the end girder *a*.

As shown in Fig. 3, the aerial cableway or main cable *b*, carrying the load-carriage *i*, is secured to a bolt *z* on the end carriage *h* by a tension-regulating and oscillating device, and the hauling-rope *j* is also attached to the carriage by a tension-regulating screwed bolt and nut.

As illustrated by Figs. 5 and 6, which are respectively a side view and a plan with the upper part removed, the load-carriage *i* may be constructed as follows: A strong framework of angled iron and the like is suspended on the main cable *b* by three wheels or pulleys 1 and carries an electromotor 2, which gives motion by the pinion 3, spur-wheel 4, and main shaft 5 and to the hauling or traveling and raising and lowering appliances. The motion is transmitted from the shaft 5, by means of the lever and clutch mechanism 6 7 8 9, to the pinion 10 and spur-wheels 11, keyed on the shaft 12, which carries the hauling-rope wheels 13. A brake-wheel 14 is also secured on the shaft 12, and a brake-band 15 on same is actuated by the pedal-actuated lever 16, lever 17, connecting-rod 18, lever 19, and bell-crank lever 20. The motion is also transmitted from the shaft 5, by means of the lever and clutch mechanism 21 22, to the pinion 23 and spur-wheel 24, secured to the duplex winding-barrel 25, revolving loose on the hollow shaft 26. The raising and lowering rope 28, being wound onto the barrel from each outer end, passes round one of the pulleys 29 of the duplex block 30, whence it passes to the compensating pulley 31 and back to the other pulley of the duplex block, so that the strain is equalized on the two parts of the rope. The winding-drum is controlled by the brake-band 32 on the brake-wheel 33, actuated by the hand-wheel 34, rod 35, and right and left handed screws screwing in the nuts 36, connected to the brake-band 32. The motive power used in this case is electricity, and any suitable arrangement or system may be employed, which will be obvious to any electrical ex-

pert and forms no part of the present invention; but it is preferred to use a three-phase current. The current generated at any convenient station is conveyed by the conducting-wires up one of the supporting-beams to the load-car, from which it is distributed to the motor 2 and the motors *k* on the end carriages. A switchboard 37 may be fitted convenient to the operator, who occupies the platform 38, where also a controller 39 is situated, and the requisite number of collector-arms 40 are employed. This arrangement of and mode of working the load and end carriage is described and illustrated by way of example and is capable of extensive modification. I therefore do not confine my claims to the details as shown and described.

Having now described my invention, what I claim as new, and desire to secure by Letters Patent, is—

1. A device for the lifting, moving and depositing of materials, comprising a foundation, supporting-beams hinged thereto and arranged in pairs at opposite ends of the device with an inclination away from each other, girders carried on said supporting-beams, and cables stretched between said girders, the weight of said supporting-beams and girders serving to put the necessary tension on the cables.

2. A device for the lifting, moving and depositing of materials, comprising a foundation, supporting-beams hinged thereto and arranged in pairs at opposite ends of the device, with an inclination away from each other, girders carried on said supporting-beams, and cables stretched between said girders, the weight of said supporting-beams and girders serving to put the necessary tension on the cables, in combination with another cable, stretched between said girders, having means at its ends to permit movement along said girders.

3. A device for the lifting, moving and depositing of materials, comprising a foundation, supporting-beams hinged thereto and arranged in pairs at opposite ends of the device with an inclination away from each other, girders carried on said supporting-beams, and cables stretched between said girders, the weight of said supporting-beams and girders serving to put the necessary tension on the cables, in combination with another cable having a carriage at each end with means carried thereby to move said cable transversely along said girders.

4. A device for the lifting, moving and depositing of materials, comprising a foundation, supporting-beams hinged thereto and arranged in pairs at opposite ends of the device with an inclination away from each other, girders carried on said supporting-beams, and cables stretched between said girders, the weight of said supporting-beams and

girders serving to put the necessary tension on the cables, in combination with another cable, a load-carriage supported thereby, and means carried by said carriage for moving 5 itself along said cable.

5. A device for the lifting, moving and depositing of materials, comprising a foundation, supporting-beams hinged thereto and arranged in pairs at opposite ends of the device with an inclination away from each other, girders carried on said supporting-beams, cables stretched between said girders, the weight of said supporting-beams and girders serving to put the necessary tension on 15 the cables, in combination with another cable, a load - carriage supported thereby having means for moving itself along said cable and means at each end of said cable for moving said cable transversely along the girders.

6. A device for the lifting, moving and depositing of materials, comprising supporting pivoted beams at opposite ends of the device, girders connecting said supporting-beams, and stay-cables stretched between said girders, in combination with load-carrying cables, a load-carriage supported on each load-carrying cable and having means to move itself along the cable, and means independent of said motive means at the end of each of the latter cables for moving the cable transversely along the girder.

7. A device for the lifting, moving and depositing of materials, comprising supporting means at opposite ends of the device, a load-cable and hauling-ropes connecting said sup-

porting means, and a framework carriage having hauling - pulleys for moving itself along the load-cable by means of the hauling-ropes, in combination with end carriages to 40 which said cables are secured, having means for moving the cables and the load-carriage transversely and means on the load-carriage for rotating the hauling-pulleys.

8. A device for the lifting, moving and depositing of materials, comprising supporting means at opposite ends of the device, a cable and hauling-ropes connecting said supporting means, and a framework carriage having means for moving itself along said cable by 45 means of said hauling-ropes, in combination with a carriage at each end of the cable and means carried by the carriage for moving the cable transversely.

9. A device for the lifting, moving and depositing of materials, comprising supporting-beams arranged in pairs at the opposite ends of the device, girders carried on said beams, a cable stretched between said girders, and a carriage adapted to travel along said cable, 50 in combination with a carriage at each end of said cable, a track along which said carriage travels and means carried by the carriage to propel itself along said track.

In testimony whereof I have signed my 55 name to this specification in the presence of two subscribing witnesses.

JOHN M. HENDERSON.
